BUSINESS MACHINE MOUNTING MEANS

Charles R. Mourey, Hartford, Conn., assignor to
Underwood Elliott Fisher Company, New York,
N. Y., a corporation of Delaware

Application February 12, 1942, Serial No. 430,567

5 Claims. (Cl. 248—19)

This invention relates to business machine mounting means and, more particularly, it is concerned with substantially avoiding the difficulty of turning a machine and resting it so as to stand its underside upright and thereby have the interior mechanism conveniently visible and accessible for inspection and servicing.

The invention is herein illustrated with reference to a combined typewriting and computing machine of the kind exemplified in the H. L. Pitman U. S. Patent No. 2,192,365, dated March 5, 1940.

In use, such a machine may rest upon a special stand or upon an office desk or table. Such a machine is heavy and its outline and bulk are such that it has not been easy to take hold of it, turn it, and rest it with its underside upright; and, of course, the same difficulty has been experienced in returning the machine to its normal position.

The usual special stand and the machine do not lend themselves for turning and resting the machine with its underside upright. To move the machine around, for this purpose, upon the usual office table or desk is not convenient either and, moreover, entails liability of marring the table or desk. Thus, under conditions as they have been, for example, in the field, the serviceman has always been handicapped in that no provision has ever been contemplated or made for enabling one to easily turn the machine over.

An object of the invention is to provide a construction for enabling one easily to turn the machine to bring its underside upright.

Another object of the invention is to provide that the machine may be easily and safely turned up and rested without removing it from its stand, desk, or table.

Another object of the invention is to embody it in structure readily and neatly applicable to existing machines.

Other features and advantages will herein-after appear.

Figure 1 is a side view of a combined typewriting and computing machine supported in normal position.

Figure 2 is a side view of the machine turned up and resting, with its underside upright, and surmounting a special stand.

Figure 3 is a perspective of a preferred form of a detail of the invention, namely, a tray with the machine resting thereon indicated in dot-and-dash outline.

Figure 4 is a transverse cross section, on the

trace 4—4, Figure 3, of the lower part of the machine resting in normal position in the tray.

Figure 5 is a top plan view of the machine resting in the tray with parts partly sectioned and broken away.

The machine includes a typewriter T secured to and surmounting a computing base B. The computing base houses computing wheels, actuators therefor indexable under control of the typewriter, general operator mechanism and numerous associated mechanisms, all generally of the kind shown in the aforesaid Patent No. 2,192,365. For simplifying the drawings, all such interior mechanisms of the computing base are represented diagrammatically in Figure 4 by the outline 10. Said interior mechanisms are supported within transversely connected side plates 11 of the computing base framework. Each side plate 11 extends longitudinally of the computing base.

An outer casing or mask 12 for the computing base may be secured to the framework and includes sides 13 skirting the framework side plates 11 and also includes front and rear skirtings 14, 15. Said sides 13 may be individual members removably attached to the side plates 11 as by snap fasteners 9.

For providing a closure for the otherwise open underside of the computing base, the latter rests upon a plate 16 having upturned lateral sides 17 contiguous to the mask sides 13 as at Figures 4 and 5. The plate 16, its sides 17 and its upturned front and rear sides 18, 19, facing the mask sides 14, 15, form a tray within which the machine is set. The tray plate 16 has, preferably four, conical elevations 20 which cooperate with recesses 21 in the bottom of the computing base for properly locating the machine within the tray. The recesses 21 may be formed in the underside of feet 22 resting upon plate 16 and having screw stems 23 for attaching the feet to the bottoms of the framework side plates 11, as in Figure 4. The tray 16—19 may be secured to the machine by screws 24 threaded into holes 25 of feet 22 and passing through washers 26 and through holes 27 centered in the conical elevations 20. Said screws 24 are used mainly for keeping the machine and tray 16—19 together during shipment, and they may be removed after the machine has been installed in an office.

The tray 16—19 may have four cushioning feet 28 of any suitable design for resting upon a stand, office table, or desk. In Figures 1 and 2, the machine is shown with the feet 28 of the tray resting upon a machine-receiving top 30 of an

individual machine stand 31 having legs 32 standing on the floor 33. When the machine is installed, the tray may be permanently secured to the stand top 30 as by means of screws 34 centered in the tray feet 28. In a similar way, the tray, and its feet 28, may be secured to the top of an office table or desk.

Each framework side plate 11 of the computing base has near its lower rear corner a stud 36 upon which is journaled a wheel 37 which, in the normal position of the machine, Figure 1, may be above and thus clear of the tray plate 16 as at 38. Referring to Figure 4, each wheel 37 is housed between the framework side plate 11 and side 13 of the mask. The side of the plate 11 may be recessed as at 35 to receive the wheel 37. Stud 36 is disposed so that the wheel projects its rim outside of the masking members 13, 15, Figure 1.

The sides 11, 13 of the computing base near the front may have holes 42 or other suitable provision for the insertion or attachment of handle-forming rods 39. If desired, the holes 42 in the masking sides 13 may be omitted and said sides may be removed preparatory to inserting the handle rods 39 in the framework sides 11. By taking hold of the inserted handle rods 39, and thereby lifting the front of the machine, the machine is turned about the point of rest of the rear machine feet 22 on plate 16 until the wheels 37 bear upon the tray plate 16, whereupon further turning of the machine takes place about the axis of said wheels 37 to lift the rear feet 22 clear of the tray plate 16. By means of the handles, one then wheels the machine forwardly upon the tray plate 16 as a track and at the same time, turns the machine further about the wheels 37 so that the machine finally is disposed in the Figure 2 position wherein the underside of the computing base stands upright and the interior of the computing base mechanism is exposed and made accessible. A rest or prop in the form of a stud 40 inserted in the rear side of the typewriter cooperates with the wheels 37 to rest the machine upon the tray plate 16 in the Figure 2 position.

The tray sides 17 may guide the machine laterally while it is being wheeled between the Figures 1 and 2 positions. It will be understood that the track of the wheels on the tray plate 16 is clear of the conical elevations 29 in that the latter may be laterally offset from said track. The wheeling of the machine to the Figure 2 position may be limited by the wheels 37 finally stopping against inner stops 41 on the tray sides 17.

The tray plate 16 may be provided with detent humps 43 in the wheel track and said humps may be forcibly overridden by the wheels 37 in wheeling the machine forwardly or rearwardly. Said humps 43 detain the machine against accidental rearward displacement from the Figure 2 position, and they also may serve as chocks against which the wheels may react while the rearward tilting of the machine is completed after the wheels have been brought against the front stops 41.

For returning the machine from its up-ended, Figure 2, position to the normal position, Figure 1, the handle rods 39 are taken hold of and the machine may be thereby pulled forwardly to tilt about the stopped wheels 37 to a suitable inclination preparatory to over-riding the detent humps 43 and wheeling the machine backwardly on the tray plate 16. The backward

wheeling of the machine may be finally limited by stopping of the wheels 37 against the rear tray side 19 so that, when the machine is finally lowered by means of the handle rods 39, its feet 22 will settle upon the tray plate 16 with the foot recesses 21 centralized over the conical elevations 29 of the tray plate 16.

By having the screw holes 27 in the tray surrounded, as indicated in the drawings, by the conical elevations 29, the latter obviate liability of any accumulated oil in the tray escaping through said holes 27.

Where the machine is installed upon the stand 31, Figure 2, the rear stand legs 32 may be provided with wheels 44 which normally are sufficiently elevated so as not to bear on the floor 33, the legs 32 being provided with non-skid feet 45 to take normally the weight of the stand and the machine to the floor. If, in wheeling the machine backwardly on the tray plate 16, it is driven with undue force against the rear tray wall 19, the resulting tendency of the stand to overturn about the rear feet 45 will bring the wheels 44 immediately to bear on the floor so that the stand and machine will merely ride upon the floor on the wheels 44 instead of overturning.

It will be obvious that it may be feasible to take hold of the machine directly, that is, without resorting to use of the handle rods 39, for wheeling the machine in the tray from one position to the other. The resting rod or rods 40 may be removed when not in use for resting the machine in the Figure 2 position.

It will be seen now that the invention provides for easily and safely handling the machine by one person and without removing the machine from its stand, desk, or table, in order to bring upright and thereby expose its underside for convenient inspection and servicing of the interior mechanism of the computing base. Conversely, the machine may be easily and safely returned to normal position.

Variations may be resorted to within the scope of the invention and portions of the improvements may be used without others.

What is claimed is:

1. In business-machine mounting-means, the combination with a supporting-plate upon which the machine is adapted to rest in normal position, of wheel-means journaled on the machine on a transverse axis near the back and bottom of the machine and adapted to engage the supporting plate for turning the machine upwardly and rearwardly about said axis and concurrently wheeling the machine forwardly upon the supporting plate to up-end and bring the machine to rest upon the plate with the underside of the machine upright.

2. In business-machine mounting-means, the machine having a footing-portion, the combination with a tray having a bottom and within which the machine is set with the footing-portion resting on said bottom, of wheel-means journaled on the machine on a transverse axis behind the footing-portion and near the back of the machine and adapted to engage the tray-bottom for turning the machine about said axis and concurrently wheeling the machine forwardly upon the tray bottom to up-end and bring the machine to rest within the tray with the underside of the machine upright, said wheel-means and axis also serving for wheeling and turning the machine back to normal position, said tray having stop-means to prevent overrun of the wheeling movements of the machine.

3. In business-machine mounting-means, the machine having a footing-portion, the combination with a tray having a bottom and within which the machine is set with the footing-portion resting on said bottom, of wheel-means journaled on the machine on a transverse axis behind the footing-portion and near the back of the machine and adapted to engage the tray-bottom for turning the machine about said axis and concurrently wheeling the machine forwardly upon the tray bottom to up-end and bring the machine to rest within the tray with the underside of the machine upright, said tray having stop-means to prevent overrun of the forward wheeling movement of the machine to up-ended position, and said bottom having a detent-hump overridable by the wheeling means and serving to detent the machine against rearward movement from its up-ended position against said stopping-means.

4. In mounting-means for a business-machine having a footing-portion, the combination with a support on which the footing-portion rests in the normal position of the machine, of wheel-means on a transverse axis near the back and bottom of the machine whereby the machine may be turned and wheeled to up-ended position in which the wheels rest on the support, and prop-means temporarily attachable to the machine

and adapted to engage said support to rest the machine in up-ended position.

5. In a business-machine mounting-means; the combination with the machine and a plate upon which the machine rests, the bottom of the machine having a plurality of formations and the plate having formations detachably fitting the machine-bottom formations so as to hold the machine and the plate against relative transverse displacement, of wheel-means journaled on the machine on a transverse axis near the back and bottom of the machine and adapted to engage the plate for turning the machine upwardly and rearwardly about said axis, and concurrently wheeling the machine forwardly upon the plate to up-end and bring the machine to rest upon the plate with the underside of the machine upright, the machine being restorable by wheeling it backwardly upon the plate and concurrently turning it forwardly and downwardly about said axis, and stop-means on the plate to engage the wheel-means to stop the backward wheeling of the machine at a position which determines that the machine and plate formations will coincide when the downward turning of the machine is completed from said position to rest the machine upon the plate.

CHARLES R. MOURAY.
